CLAIM

We claim the ornamental design for a model vehicle pivoting axle carrier, as shown and described.

DESCRIPTION

FIG. 1 is an upper, right, front perspective view of a model vehicle pivoting axle carrier showing our new design;

FIG. 2 is a front side view thereof;

FIG. 3 is a rear view thereof;

FIG. 4 is a left side elevation view thereof;

FIG. 5 is a right side elevation view thereof;

FIG. 6 is a lower elevation view thereof;

FIG. 7 is an upper elevation view thereof;

FIG. 8 is an upper, left, rear perspective view thereof; and, FIG. 9 is a lower, left, front perspective view of the model vehicle pivoting axle carrier.

In the drawings, the broken lines illustrate portions of the model vehicle pivoting axle carrier that form no part of the claimed design.
